CONCRETE ROOF-TILE.

1,030,590.

Specification of Letters Patent.

Patented June 25, 1912.

Application filed March 6, 1911. Serial No. 612,436.

To all whom it may concern:

Be it known that I, FRED LATULIP, of Syracuse, in the county of Onondaga, in the State of New York, have invented new and 5 useful Improvements in Concrete Roof-Tile, of which the following, taken in connection with the accompanying drawings, is a full, clear, and exact description.

This invention relates to certain improvements in concrete corner tiles somewhat similar to that shown in my Patent #907,824 issued December 29, 1908 except that it is especially adapted for edge finishing of cornices and gutters of roofs and 15 other places where such finishing is desirable.

The main object, therefore, is not only to provide the overlapping ends and edges of the tile with locking members for interlocking engagement with each other and with the rafters or furring strips but also to provide the tile with pendant lengthwise finishing flanges extending along one edge thereof so as to lie in coincident planes with 25 their lower edges in straight lines for the purpose of giving a better edge finish to the roofing or siding and at the same time forming a water and air-tight joint with the main body of the roof or cornice.

30 Other objects and uses will be brought out in the following description.

In the drawings:—Figure 1 is a perspective view of a portion of a roof showing a series of my improved tiles assembled 35 thereon. Fig. 2 is an end view of a portion of a gable roof showing in more detail the manner of applying the tiles including the cornice tiles. Fig. 3 is a transverse sectional view of a series of assembled tiles 40 showing a pair of rafters in dotted lines and auxiliary lugs coacting with the cornice flanges to hold the tile against relative lateral movement on the roof. Fig. 4 is a perspective view of an inverted left hand tile. 45 Fig. 5 is a perspective view of an inverted half-tile for right hand cornice. Fig. 6 is a perspective view of a right hand cornice tile. Fig. 7 is a perspective view of a portion 50 of a roof gutter or valley showing the manner of applying the gutter and my improved tile thereto. Fig. 8 is a perspective view of one of the valley tiles shown in Fig. 7.

In Figs. 1, 2 and 3, I have shown a series 55 of plain roof tile —1— and another series

of cornice tile —2— adapted to be used in connection with the plain tile —1— for finishing the edge or cornice of the tile roofing, the ridge of the roof being capped by a series of what may be termed ridge 60 tile —3—. These tiles are preferably made of cement or concrete of uniform shape and size except where necessary to use half-widths and are assembled upon the roof in such manner as to break joints similar to 65 laying slate or shingle roofing, each tile consisting of a substantially thin flat plate or main body —4— having one of its longitudinal edges provided with a pendant flange —5— running parallel with its opposite edge but somewhat shorter than the main body as will be hereinafter more fully described. The main body or plate —4— may be reinforced by one or more lengthwise ribs —6— and a suitable metal reinforcement —7— embedded therein and preferably extending into the pendant flange —5— so as to strengthen and prevent breakage of the corner. 70

The plain tile —1— forming the main 80 body of the roofing are very similar to those shown and described in my patent referred to except that the interlocking transverse ribs are closer to the ends to reduce the amount of lap and thereby exposing by far 85 the greater portion of the tile to the weather and permitting a considerably greater area to be covered with the same number of tiles. For this purpose each of the tiles —1— is provided near one end with a pendant transverse rib —8— on the lower side thereof close to such end, while the upper end is provided with a corresponding transverse groove —9— in the upper face thereof and substantially the same distance from the upper 90 end as the rib —8— is from the lower end so that when the rib —8— of one tile is seated in the corresponding groove —9— of the underlying tile, the length of lap is approximately equal to twice the distance 95 from the end of the tile to the corresponding rib —8— or to the corresponding groove —9—.

The opposite lengthwise edges of the tiles 100 —1— are provided respectively in their lower and upper sides with lengthwise grooves forming laps —10— which are comparatively narrow transversely, the contiguous faces of thelapping portions —10— being beveled or undercut transversely to es- 105 110

tablish an interlocking connection between adjacent tiles and thereby prevent their relative lateral movement. The inner edges of the cornice tile —2— are also formed 5 with similar lapping portions —10— interlocking with the corresponding edges of the plain tile —1— but the main feature of the invention lies in providing these tile with pendant edge finishing flanges —5— as used 10 for cornice or with similar pendant flanges —5'— for giving a finish to the gutter or valley tile shown in Figs. 7 and 8. These tiles are additionally held in place upon the roof against downward displacement by 15 shoulders —12— which are formed integrally on the underside of the upper ends of the tile and interlock with suitable furring strips —13— as best seen in Figs. 2, 4 and 8. As an additional means for holding the 20 cornice and gutter tile against lateral displacement from the roof, they are provided with one or more integral pendant lugs or flanges —14— spaced apart from the lengthwise edge flanges —5— or —5'— a distance 25 corresponding to or slightly greater than the thickness of one of the rafters as —a— so that the flanges —5— or —5'— will engage one side of a rafter, while the lugs or flanges —14— will engage the opposite side 30 of the same rafter, thereby holding the tile against relative movement thereon.

It will be observed upon reference to Figs. 1 and 2 that in laying the tile upon the roof, each course will be disposed at an angle in- 35 stead of parallel with the rafters, that is, the lower ends of the tile will be spaced apart a greater distance from the rafter than their upper ends, a distance corre- 40 sponding to the thickness of the underlap- ping portion of the adjacent tile and in order that the lower edges of the flanges —5— of the cornice tile may lie in the same straight line, they are tapered from their lower ends toward their upper ends at sub- 45 stantially the same angle to the main body of the tile as that between the tile and upper edge of the rafters, as more clearly shown at the right of Fig. 2. These pendant flanges —5— of the cornice tile are some- 50 what shorter than the length of the main body, the difference in length being sub- stantially equal to the degree of the end lap of the tiles one upon the other, thereby forming a recess —15— at the upper end 55 of the flange —5— for receiving the lower end of the adjacent flange and permitting the flanges of adjacent tile to abut end to end and to lie in the same vertical plane. As more clearly shown in Fig. 2, the abut- 60 ting ends of these flanges are beveled or inclined so as to overlap or partially interlock one with the other to aid in holding the assembled cornice tiles in place and at the same time rendering the joints substan- 65 tially water proof and air tight. In prac-

tice the wider end of the flange is prefer- ably recessed at —16— to receive the smaller end of the next adjacent flange, thereby permitting the superposed portions of the lower end of the cornice tile to overlap upon the 70 upper ends of the next adjacent tile.

It is apparent from the foregoing de- 75 scription that the flanges —5— of the cornice tile overturn upon the upper edges of the cornice rafters or frieze and lie in sub- stantially the same vertical plane to give the desired finish to the edge of the roofing and also to establish a weather tight joint with this portion of the building structure, while the flanges —5'— of the gutter tile 80 shown in Figs. 7 and 8 perform a similar function at this part of the building.

In like manner I have shown a series of ridge tile —3— having end flanges —18— abutting against the adjacent ends of the flanges —5— of the cornice tile, said ridge tile being also provided with ribs —8— for interfitting engagement in the grooves —9— in the upper ends of the adjacent tiles —1— and —2—, the meeting ends of the ridge 90 tile —3— being provided with interlocking tongues and grooves as more clearly shown in Fig. 1 to hold them against relative end- wise movement.

The valley tile as shown in Fig. 7 are 95 arranged at opposite sides of the valley rafter as —a'— and have their flanges —5'— and —14— interlocked with opposite sides of furring strips —17— which are se- cured to the upper faces of the rafter —a— 100 at opposite sides of and parallel with the valley rafter —a'—. Prior to the laying of the valley tile, the valley is covered with a tin or other metallic gutter —20— extending across the upper face of the valley rafter —a'— and adjacent ends of the rafter —a— and over the upper face of the furring strips —17— so as to underlie the overhanging portions of the valley tile —4'—. 110

It will be observed that these different forms of tiles are provided with similar means for locking them together and that the cornice and valley tiles are also pro- 115 vided with additional locking members co- acting with the finishing flanges for further holding them in operative position against shifting movement on the roof.

What I claim is:

An edge finishing tile having one end 120 thereof provided with a transverse groove in its upper face and its other end provided with a transverse rib upon its lower face, both the said groove and rib being spaced from the ends of the tile, a length-wise 125 flange provided upon one longitudinal edge of the tile and extending from a point at the inner side of the groove to a point beyond the rib, the said flange tapering from the rib and toward the said groove, a 130

longitudinal groove extending the entire length of the tile edge upon the side thereof opposite to the flange, a longitudinally-positioned depending lug upon the under side 5 of said tile and slightly spaced from the depending flange thereof, a terminal shoulder upon the lower face of said tile at the end thereof opposite to the said rib, and said

tile adapted to interlock with other similar tiles when positioned in assembled relations. 10

In witness whereof I have hereunto set my hand on this 27th day of February 1911.

FRED LATULIP.
